UNITED STATES PATENT OFFICE.

BEARL E. COLBURN, OF GREEN BAY, WISCONSIN, ASSIGNOR TO SUPER-BALL
ANTENNA CO., INC., OF GREEN BAY, WISCONSIN.

DESIGN FOR A LOUD SPEAKER.

Application filed August 31, 1927. Serial No. 23,255. Term of patent 7 years.

To all whom it may concern:

Be it known that I, BEARL E. COLBURN, a citizen of the United States, and a resident of Green Bay, in the county of Brown and State of Wisconsin, have invented a new, original, and ornamental Design for a Loud Speaker, of which the following is a specification, reference being had to the accompanying drawing, forming part thereof.

Figure 1 is a front elevation of the loud speaker.

Figure 2 is a side elevation of the loud speaker.

I claim:

The ornamental design for a loud speaker, as shown.

In testimony that I claim the foregoing I have hereunto set my hand at Green Bay, in the county of Brown and State of Wisconsin.

BEARL E. COLBURN.
